UNITED STATES PATENT OFFICE.

JOHN J. KORAN, OF OKLAHOMA CITY, OKLAHOMA.

DESIGN FOR RADIATOR CAP.

Application filed November 2, 1925. Serial No. 15,328. Term of patent 7 years.

To all whom it may concern:

Be it known that I, JOHN J. KORAN, a citizen of the United States, residing at Oklahoma City, in the county of Oklahoma and State of Oklahoma, have invented a new, original, and ornamental Design for Radiator Caps, of which the following is a specification, reference being had to the accompanying drawing, forming a part thereof.

The Figure 1 is a plan view of the radiator cap, and Figure 2 is an elevation view of the radiator cap, showing my design.

I claim:

The ornamental design for the radiator cap, as shown.

JOHN J. KORAN.
